UNITED STATES PATENT OFFICE.

GEORGE W. JESSUP, OF BOSTON, MASSACHUSETTS.

SYRINGE NOZZLE-POINT.

1,243,840.

Specification of Letters Patent. Patented Oct. 23, 1917.

Application filed June 7, 1916. Serial No. 102,204.

To all whom it may concern:

Be it known that I, GEORGE W. JESSUP, a citizen of the United States, and a resident of Boston, in the county of Suffolk 5 and State of Massachusetts, have invented a new and Improved Syringe Nozzle-Point, of which the following is a full, clear, and exact description.

This invention relates to syringe points 10 of that type disclosed in United States Letters Patent 856,093, granted to H. F. Ong, June 4, 1907, in which the syringe is formed with a pneumatic bulb which forms the base of the flexible injection tube so that, when 15 the said tube is inserted into the organ to be treated, the bulb serves as a stopper so as to retain the treating solution in the organ.

The object of the present invention is to 20 improve the pneumatic bulb so that the user can from time to time force air into the bulb for restoring the internal pressure. In the said patent the bulb is hermetically sealed, but in the course of time the air 25 pressure is considerably lessened so that the bulb does not act as efficiently as a stopper, and by means of the present invention the user can restore the air pressure conveniently when it is necessary, and furthermore, a small quantity of water—a teaspoonful—can 30 be added once a year to keep the bulb moist and pliable, preventing cracking.

A more specific object of the invention is 35 the provision of an inflation tube permanently attached to the bulb and leading into the same, in combination with a stopper, whereby the air forced through the tube when the stopper is opened, can be held in the bulb.

With such objects in view, and others 40 which will appear as the description proceeds, the invention comprises various novel features of construction and arrangement of parts which will be set forth with particularity in the following description and 45 claims appended hereto.

In the accompanying drawing, which illustrates certain embodiments of the invention and wherein similar characters of reference indicate corresponding parts in all the views, 50 Figure 1 is a side view of the nozzle point; Fig. 2 is a longitudinal section thereof; and

Fig. 3 is a longitudinal section of a modified form of inflation tube.

55 Referring to the drawing, 1 designates the soft rubber syringe tube which passes axi-

ally through the bulb 2 and has an injection portion or nozzle 3 which has a lateral outlet 4 for the discharge of the solution into the organ that is treated. The bulb 2 has 60 a chamber 5 which is adapted to contain air under pressure, and if desired, a small amount of liquid 6 may be confined therein so as to keep the internal surface of the bulb moist and thereby prolong the life of 65 the rubber.

In the construction shown in Figs. 1 and 2 the bulb has a short rubber tube 7 extending into it, and this tube is vulcanized to the main tube 1 and to the wall of the 70 bulb so that joints are avoided. The tube extends into the bulb a short distance and projects out of the bulb a greater distance, although this feature is not important, except that a suitable portion of the tube is 75 disposed outside the bulb for convenience in controlling the inflation. The outer end of the tube is closed by a suitable stopper 8 which is adapted to be removed when the bulb is to be inflated. When the stopper 80 is removed the bulb can be inflated in any suitable manner. The outer end of the tube 7 can be inserted in the user's mouth and air blown into the chamber 5 of the bulb 2. Or a small piece of tubing can be inserted 85 in the tube 7 and air blown through this tubing into the bulb. When the desired pressure is obtained, the tube 7 is compressed at the point 9 by pressing the thumb or finger against the tube, so that 90 no air can escape, and while it is thus held compressed the stopper 8 is inserted.

With a hermetically sealed bulb it seems 95 that in a year or two, or in less time, the air loses its pressure, and therefore means for restoring the pressure, as herein described, is desirable, so as to increase the life of the device. If desired, an inflating tube 7^a can be provided, as shown in Fig. 3, and in this tube a stopper in the form of a check valve 100 10 is employed, which permits of the ready inflation of the bulb without removing the stopper, the pressure inside the bulb serving to maintain the ball of the check valve closed. It will be noted that the inner end 105 of the tubes 7 and 7^a by projecting into the bulb a suitable distance, serves as a trap so that the liquid 6 cannot enter the tube and work out.

By providing a removable stopper in the 110 air tube the latter can be opened when the device is boiled for sterilizing. If the

syringe were placed in boiling water without the stopper 8 removed, the liquid 6 in the bulb would be converted into steam and produce a destructive internal pressure. 5 Even if the pressure is not sufficient to burst the bulb it will make the latter increase considerably in size and cause a permanent weakening of the wall of the bulb at its weakest point, so that the bulb could not 10 return to its normal size or shape. After it has been sterilized the bulb is inflated and a small quantity of fluid supplied before sealing, as has been described.

From the foregoing description taken in 15 connection with the accompanying drawing, the advantages of the construction and method of operation will be readily understood by those skilled in the art to which the invention appertains, and while I have 20 described the principle of operation, together with the device which I now consider to be the best embodiment thereof, I desire to have it understood that the device shown is merely illustrative and that such 25 changes may be made when desired as fall within the scope of the appended claims.

Having thus described my invention, I claim as new and desire to secure by Letters Patent:

30 1. A syringe nozzle point comprising an injection tube of rubber, a pneumatic rubber bulb surrounding the tube, with both ends of the latter projecting from the bulb and integrally connected with the latter, a second rubber tube of such length as to ex-

tend partly into the bulb and having one end projecting out of the same, the latter tube being integrally connected with the bulb and flexible, and a stopper in the outer end of the second tube for permitting air 40 under pressure to be maintained in the bulb.

2. A syringe nozzle point comprising a solution tube, a pneumatic bulb surrounding the tube, a short tube parallel with the first-mentioned tube and communicating with the bulb for permitting the latter to be inflated with air and a preservative fluid to be supplied, said short tube having a portion exterior to the bulb, whereby it can be pinched to hold the air in the bulb preparatory to the insertion of a stopper in the short tube, and a stopper closing the outer end of the short tube. 45 50

3. A syringe nozzle point comprising a rubber bulb, two rubber tubes substantially 55 parallel with each other and integrally connected, one tube extending entirely through the bulb and out of communication therewith for conducting fluid, and the other tube extending through the wall of the bulb and communicating with the interior of the latter, said tube being integrally connected with the bulb, and a stopper in the outer end of the tube communicating with the bulb. 60
